UNITED STATES PATENT OFFICE.

IRVING R. COCKROFT, OF ALAMEDA, CALIFORNIA.

PUMP.

1,351,505.

Specification of Letters Patent. Patented Aug. 31, 1920.

Application filed January 28, 1920. Serial No. 354,679.

To all whom it may concern:

Be it known that I, IRVING R. COCKROFT, a citizen of the United States, residing at Alameda, in the county of Alameda and State of California, have invented new and useful Improvements in Pumps, of which the following is a specification.

This invention relates to a pump and especially to a pump of the reciprocating piston type.

One of the objects of the present invention is to provide a simple and substantial pump of the reciprocating piston type and especially a double acting pump in which all valves, except a foot valve, may be entirely eliminated.

Another object of the invention is to construct a pump consisting of a stationary and a floating cylinder; further to form ports in the floating cylinder which are so arranged that they alternately serve as intake and discharge ports, thus producing a double acting pump without the use of ordinary valves which are so liable to wear and leakage, particularly if the water or liquid handled contains gritty matter or the like.

Further objects will hereinafter appear.

The invention consists of the parts and the construction, combination and arrangement of parts as hereinafter more fully described and claimed, having reference to the accompanying drawings, in which—

Figure 1 is a central vertical longitudinal section of the pump taken on line 1—1, Fig. 2.

Fig. 2 is a cross section on line 2—2, Fig. 1.

Fig. 3 is a perspective view of one of the main cylinder sections.

Fig. 4 is a perspective view of one of the main cylinder heads.

Referring to the drawings in detail, A indicates in general a main cylinder, the ends of which are closed by cylinder heads shown at 2 and 3 respectively. Mounted interiorly of the main cylinder is a floating cylinder 4 and forming a closure therefor are cylinder heads as shown at 5 and 6 respectively. The main cylinder A consists of two sections 7 and 8, (see Figs. 2 and 3) the cylinder being divided longitudinally as at 9 to form the sections 7 and 8. These sections are secured together by bolts 10 and offset seats 11 are provided to form a leak-proof joint or connection between the same. The heads 2 and 3 are constructed substantially as shown in Fig. 4 and are secured to

the main cylinder by means of bolts 12. One of the heads, or that shown at 3, is provided with a stuffing box 14 through which extends 60 a piston rod 15. This piston passes through the head 3 and also through the head 6 of the inner floating cylinder, being connected at its inner end with a piston 16 of suitable construction. This piston travels within the 65 floating cylinder only and reciprocal movement may be transmitted thereto from any suitable source of power not here shown.

The pump, as shown in Figs. 1 and 2, is divided into a main cylinder chamber 17 and 70 three exterior chambers as indicated at 18, 19 and 20, the chambers 18 and 19 being formed between the respective heads 2—5 and 3—6, while the chamber 20 is annular and is formed between the inner and the exterior cylinder. Connecting the end chambers 18 and 19 is a longitudinally extending port 21 which terminates in a discharge connection 22, and connected with the annular chamber 20 is an inlet connection 23 in 80 which is mounted a foot valve 24.

Formed on the interior surface of the main cylinder A are a pair of annular shoulders 25 and 26, and formed in the respective sides of each annular shoulder are grooves 85 for the reception of resilient seat members 27, said seat members being constructed of rubber, leather or other suitable material. The inner cylinder heads 5 and 6 are larger in diameter than the exterior diameter of 90 the inner floating cylinder. They therefore form projecting annular shoulders 28 and 29 which are adapted to engage the resilient seat members 27 supported by the annular shoulders 25 and 26. The inner cylinder is 95 furthermore provided with a pair of annular shoulders 30 and 31. The diameter of these shoulders is equal to the exterior diameter of the heads 28 and 29 and they are therefore in a position to engage the 100 resilient seat members 27, the annular shoulders 30 and 31 engaging the seat members on the inner side of the shoulders 25 and 26 and the shoulders 28 and 29, the seat members 27 supported on the exterior sides 105 of the annular shoulders 25 and 26.

The operation of the pump as a whole is substantially as follows:

With the reciprocal movement imparted to the piston 16 by means of the piston rod 15, it can be seen that movement of the piston in the direction of arrow "a" will cause endwise movement of the floating cylinder 4 in the same direction, the movement of the

floating cylinder being, however, limited in this direction by means of the annular shoulders 29 and 30 when they engage their respective seat members 27. This endwise movement of the floating cylinder brings a plurality of ports 40 formed in one end thereof in register with the annular chamber 20 and the inlet connection 23, and it simultaneously brings a series of ports 41 formed in the opposite end of the cylinder into register with the end chamber 18 and the discharge port 21. Continued movement of the piston in the direction of arrow "a" will cause liquid contained therein to discharge through the ports 41 into the chamber 18 and will therefore permit it to discharge through the port 21 and the connection 22. The liquid will, at the same time, be admitted through the connection 23 and valve 24 to the annular chamber 20 and from said chamber liquid will enter ports 40 and the chamber 17 formed within the floating cylinder proper. Reverse movement of the piston when it reaches the end of its stroke will first of all cause a slight pressure of the liquid admitted during the suction stroke and will, secondly, cause endwise movement of the floating cylinder until the shoulders 28 and 31 engage their respective resilient seat members 27 supported by the annular shoulders 25 and 26. Ports 40 will then register with the chamber 19 and the discharge passage formed by the port 21, while the ports 41 will register with the annular chamber 20 and the intake connection 23. Liquid will in this manner alternately enter and discharge and the function of the pump will be double acting, this being accomplished without the use of ordinary valves which are generally subject to cutting action and wear, particularly if a certain amount of gritty material is handled, and the life of the pump will accordingly be comparatively great. This is of great importance, particularly in deep well work, and in other installations, as it is practically impossible under certain conditions to give ordinary valves proper attention.

The efficiency of a pump of this character should be great as valve wear and leakage is, practically speaking, entirely eliminated and under all conditions at least negligible, the resilient seat members 27 being constructed of leather, rubber or the like, first of all absorbs any shock due to endwise movement of the floating cylinder; secondly, they always form a leak-proof connection as a slight amount of grit that might have a tendency to hold an ordinary valve away from the seat will in this instance merely become embedded in the resilient seating material and will therefore not only reduce wear but also prevent leakage. They should accordingly last for almost indefinite periods as slight compression of the same

will not materially affect the operation of the pump, due to the fact that the stroke of the floating cylinder is not limited, that is, it may be increased to a considerable extent without materially reducing the efficiency of the pump.

Where a pump of this character is operated under comparatively high speed, it should be obvious that a foot valve might be eliminated. This is due to the fact that the alternate position assumed by the ports 40 and 41 is changed so rapidly that comparatively little water would have a chance to escape through the suction during the reverse movement of the piston. Even a foot valve may therefore be eliminated under certain conditions.

While a more or less specific structure is shown, I wish it understood that various changes in form and proportion may be resorted to within the scope of the appended claims, similarly that the materials and finish of the several parts employed may be such as the experience and judgment of the manufacturer may dictate or varying conditions may demand.

Having thus described my invention, what I claim and desire to secure by Letters Patent is—

1. A pumping apparatus comprising two concentric interspaced cylinders, a head member secured on each end of the outer cylinder, inlet and outlet passages formed in the outer cylinder, a foot valve mounted in the intake passage, a pair of interior flanges formed on the outer cylinder, and interior thereof, said flanges disposed one adjacent each end of the cylinder and forming a sliding support for the inner cylinder, a pair of flanges formed on each end on the inner cylinder and alternately closable against the stationary flanges formed on the outer cylinder, ports formed in the inner cylinder between the flanges, a piston within the inner cylinder, and a piston rod connected therewith and extending through both cylinders.

2. In a pumping apparatus of the character described the combination with the outer cylinder and the interior flanges formed one at each end thereof, of an inner cylinder slidably mounted in said flanges, said inner cylinder having a head member formed at each end and a pair of flanges formed at each end, which are interspaced and adapted to alternately engage the first named flanges, and ports formed at each end of the inner cylinder between the flanges.

3. A pump comprising a main cylinder and an interior floating cylinder, a piston reciprocally mounted within the floating cylinder, a piston rod connected therewith extending through both cylinders, a discharge and an intake connection formed on the exterior cylinder, a head member on each end

of the floating cylinder; ports formed in each end of the floating cylinder, a pair of annular shoulders formed in each end of the floating cylinder, a pair of annular shoulders formed on the interior surface of the main cylinder, one at each end thereof, said shoulders dividing the interior of the main cylinder into a pair of end chambers and a central annular chamber, said 10 central annular chamber communicating with the intake connection and said end chambers both communicating with the discharge connection.

4. A pump comprising a main cylinder and an interior floating cylinder, a piston reciprocally mounted within the floating cylinder, a piston rod connected therewith extending through both cylinders, a discharge and an intake connection formed on the exterior cylinder, a head member on each end of the floating cylinder, ports formed in each end of the floating cylinder, a pair of annular shoulders formed in each end of the floating cylinder, a pair of annular shoulders formed on the interior surface of the main cylinder, one at each end thereof, said shoulders dividing the interior of the main cylinder into a pair of end chambers and a central annular chamber, said 20 central annular chamber communicating with the intake connection and said end chambers both communicating with the discharge connection, and seat members formed on the respective sides of the annular shoulders formed within the main cylinder.

5. A pump comprising a main cylinder and an interior floating cylinder, a piston reciprocally mounted within the floating cylinder, a piston rod connected therewith extending through both cylinders, a discharge and an intake connection formed on the exterior cylinder, a head member on each end of the floating cylinder, ports formed in each end of the floating cylinder, a pair of annular shoulders formed in each end of the floating cylinder, a pair of annular shoulders formed on the interior surface of the main cylinder, one at each end thereof, said shoulder dividing the interior of the main cylinder into a pair of end chambers and a central annular chamber, said central annular chamber communicating with the intake connection and said end chambers both communicating with the discharge connection, set members formed on the respective sides of the annular shoulders formed within the main cylinder, and a valve mounted in the intake connection.

6. In a pumping apparatus of the character described the combination with the outer cylinder and the interior flanges formed one at each end thereof, of an inner cylinder slidably mounted in said flanges, said inner cylinder having a head member 65 formed at each end and a pair of flanges

formed at each end, which are interspaced and adapted to alternately engage the first named flanges, ports formed at each end of the inner cylinder between the flanges, and means for imparting a limited reciprocal movement to the inner cylinder to bring the ports intermittently into register either with an end chamber or a central annular chamber formed between the exterior cylinder and the inner cylinder.

7. In a pump of the character described, a main cylinder and a floating cylinder, a pair of end chambers and a central annular chamber formed between the main cylinder and the floating cylinder, peripherically arranged ports formed in each end of the floating cylinder, a piston reciprocally mounted in the floating cylinder and adapted to impart a reciprocal movement to the floating cylinder, a pair of annular shoulders formed at each end of the floating cylinder and at opposite sides of the peripherically arranged ports, and a pair of annular shoulders formed in the main cylinder, one between each pair of annular shoulders formed on the floating cylinder, said annular shoulders adapted to limit the reciprocal movement of the floating cylinder and intake connection formed on the main cylinder communicating with the annular chamber and the piston connection formed on the main cylinder communicating with the end chambers.

8. In a pump of the character described, a main cylinder and a floating cylinder, a pair of end chambers and a central annular chamber formed between the main cylinder and the floating cylinder, peripherically arranged ports formed in each end of the floating cylinder, a piston reciprocally mounted in the floating cylinder and adapted to impart a reciprocal movement to the floating cylinder, a pair of annular shoulders formed at each end of the floating cylinder, and at opposite sides of the peripherically arranged ports, a pair of annular shoulders formed in the main cylinder, one between each pair of annular shoulders formed on the floating cylinder, said annular shoulders adapted to limit the reciprocal movement of the floating cylinder, and intake connection formed on the main cylinder communicating with the annular chamber and the discharge connection formed on the main cylinder communicating with the end chambers, and resilient seat members supported on each side of the annular shoulders formed in the main cylinder.

In testimony whereof I have hereunto set my hand in the presence of two subscribing witnesses.
